UNITED STATES PATENT OFFICE

168,390

BOTTLE

William H. Baird, Wheeling, W. Va., assignor to
Hazel-Atlas Glass Company, Wheeling, W. Va.,
a corporation of West Virginia

Application October 29, 1952, Serial No. 22,042

Term of patent 14 years

(Cl. D58—8)

To all whom it may concern:

Be it known that I, William H. Baird, a citizen of the United States, residing at Wheeling, in the county of Ohio, and State of West Virginia, have invented a new, original, and ornamental Design for a Bottle, of which the following is a specification, reference being had to the accompanying drawing, forming part thereof.

Figure 1 is a front perspective view of a bottle showing my new design;

Figure 2 is a side elevational view thereof;

Figure 3 is a top plan view thereof; and

Figure 4 is another perspective view thereof.

I claim:

The ornamental design for a bottle, as shown.

WILLIAM H. BAIRD.
